ATTY

UNITED STATES PATENT OFFICE.

ALPHIE E. GETZ, OF PEORIA, ILLINOIS.

MEANS FOR COOLING BRICKWORK OF FURNACES.

Application filed March 27, 1926. Serial No. 97,942.

This invention has reference to means for cooling the brickwork of furnaces and has special reference to a means for cooling the skewbacks and the roof of open hearth furnaces.

The invention comprehends the application of ducts in or between the units forming the skewbacks of a furnace and in the provision of a source of air supply thereto; 10 the ducts of air entering into or between the units forming such skewbacks not only cooling the same but such air will find its way up to and along the under side of the roof of the furnace and tend to keep such roof 15 cool for a considerable distance from such skewbacks.

When cooling means are not provided for skewbacks of open hearth furnaces, the skewbacks and that part of the roof adjacent thereto become overheated and under normal conditions is the first part of the roof structure to burn away. I am aware of 20 water cooling means for skewbacks, but these all function from outside the furnace and 25 are usually limited to the cooling of four or five inches of the thickness of the brickwork. My invention works on the inside of the furnace and cools the brickwork, and 30 keeps it cool by feeding a continuous supply of cold air along the skewbacks and the roof adjacent thereto.

That the invention may be more fully understood reference is had to the accompanying drawings forming a part of the 35 description, illustrating a preferred embodiment in which:-

Fig. 1 is a cross-section on a greatly reduced scale showing a part of a conventional form of open hearth furnace with my invention applied thereto;

Fig. 2 is a detail in cross-section as the same would appear if taken on the line 2-2, Fig. 1, looking in the direction of the arrows; and

Fig. 3 is a perspective view of an element for conducting cold air to the skewbacks.

Like characters of reference denote corresponding parts thruout the figures.

In the drawings so much of a furnace is shown to illustrate the application of my cooling means thereto, and includes the front and back walls 1 and 2, the arched roof 3, and the skewbacks 4 connecting the front and back walls of said roof.

The units comprising the skewbacks are 55 provided with air ducts 5, which are preferably inclined inwardly and upwardly, as shown, and may be within the units themselves or formed by matching recesses in their adjacent faces. Disposed alongside 60 and adjacent the outer faces of the front and back walls 1 and 2 are air conducting pipes 6 provided with or having connected thereto nozzles 7, which preferably project into the ducts 5. Said pipes 6 are connected 65 with feeders 8 which, in turn, are connected with any suitable source of air supply, under pressure, not shown.

In operation, air supplied to the feeders 8 is conducted thru the pipes 6, the nozzles 7, and into and thru or between the members constituting the skewbacks 4, and such air entering the interior of the furnace travels upwardly along the skewbacks and in contact with and on the underneath side 75 of the roof 3.

The function of the air is to increase the life of the skewbacks and roof by keeping a constant stream of relatively cold air circulating along their inner sides. This not 80 only keeps these members cool but also tends to keep away the hot gases forming a part of the products of combustion in the interior of the furnace.

Although I have described this for skewbacks and roofs of furnaces, it is obvious that my cooling means may be applied to other furnace parts.

What I claim is:-

1. A furnace, certain of the walls of which are provided with air ducts in proximity to the roof and inclined towards the same, and means for supplying relatively cold air to said air ducts, the latter, due to their inclination, adapted to discharge such air 95 as to cause it to travel interiorally over a part of such walls and roof surface.

2. A furnace provided with skewbacks extending along certain of its walls, said skewbacks arranged with air ducts for the introduction of air, so directed as to cool said skewbacks and the portions of the roof immediately adjacent thereto, and means for supplying a source of relatively cold air to said air ducts.

ALPHIE E. GETZ.
